UNITED STATES PATENT OFFICE.

GEORGE N. JOSS, OF INDIANAPOLIS, INDIANA, ASSIGNOR TO THE EAGLE
MACHINE COMPANY, OF LANCASTER, OHIO.

DESIGN FOR A VENTILATOR-GRADE.

SPECIFICATION forming part of Design No. 21,800, dated August 23, 1892.

Application filed July 19, 1892. Serial No. 440,538. Term of patent 7 years.

To all whom it may concern:

Be it known that I, GEORGE N. JOSS, a citizen of the United States, residing at Indianapolis, in the county of Marion and State of Indiana, have invented and produced a new and original Design for Ventilator-Grates; and I do hereby declare the following to be a full, clear, and exact description of the same, reference being had to the accompanying drawings, forming a part thereof.

In the drawings, Figure 1 is a perspective view of a ventilator-grate embodying my design, and Fig. 2 is a sectional view taken on the line $x-x$ of Fig. 1.

15 A designates a lattice or reticulate work, which is provided with ribs B, raised above the bars constituting the ground of the structure. In the instance shown the ribs are in

the form of crosses lying transversely of the lattice-work. Surrounding the lattice-work is a frame C, which is deeper and heavier than the ribs B.

The important feature of my design consists in the ribs B, which are raised above or are deeper than the bars forming the ground or the body of the lattice-work.

What I claim is—

The design for a ventilator-grate, substantially as shown and described.

In testimony whereof I affix my signature in presence of two witnesses.

GEORGE N. JOSS.
